(57) **CLAIM**

The ornamental design for a loudspeaker housing, as shown and described.

DESCRIPTION

FIG. 1 is a perspective view of a loudspeaker housing showing my new design;

FIG. 2 is a top plan view thereof;

FIG. 3 is a side elevational view, the opposite side elevational view being a mirror image thereof;

FIG. 4 is a bottom plan view thereof;

FIG. 5 is a front elevational view thereof; and,

FIG. 6 is a rear elevational view thereof.

The broken line showings of the teardrop shape on the front of each of the four lobes; and the shaft and cord extending rearward are for illustrative purposes only and form no part of the claimed design.
